(57) **CLAIM**

We claim the ornamental design for a sample deck for selecting a covering for an architectural opening, as shown and described.

DESCRIPTION

FIG. 1 is a front isometric view of a sample deck for selecting a covering for an architectural opening.

FIG. 2 is a rear isometric view thereof.

FIG. 3 is a front elevation view thereof.

FIG. 4 is a rear elevation view thereof.

FIG. 5 is a bottom plan view thereof. The top plan view is a mirror image of the bottom plan view; and,

FIG. 6 is a left side elevation view thereof. The right side elevation view is a mirror image of the left side elevation view.

The broken lines in FIGS. 1-6 illustrate portions of a sample deck for selecting a covering for an architectural opening that form no part of the claimed design.
